(57) **CLAIM**

The ornamental design for a tire for automobile, as shown and described.

DESCRIPTION

1. Tire for automobile
- 1.1 is a front elevation view of a tire for automobile showing my new design;
- 1.2 is a rear elevation view thereof;
- 1.3 is a top plan view thereof;
- 1.4 is a bottom plan view thereof;
- 1.5 is a right side elevation view thereof;
- 1.6 is a left side elevation view thereof;
- 1.7 is a perspective view thereof; and,
- 1.8 is an enlarged partial front elevation view thereof, wherein the enlargement area is indicated by the broken line bracket marked **1.8** in **1.1**.
The ghosted or low contrasted showing of portions of the tire for automobile do not form part of the claimed design.
